WAFFLE COOKING PLATE

Alfred M. Price, Crystal Lake, Ill., assignor to
The Quaker Oats Company

Filed June 4, 1970, Ser. No. 23,308

Term of patent 14 years

Int. Cl. D7—02

U.S. Cl. D44—1

FIG. 1 is a perspective view of a waffle cooking plate showing my new design;

FIG. 2 is a top plan view;

FIG. 3 is a left end elevational view;

FIG. 4 is a right end elevational view;

FIG. 5 is a front elevational view;

FIG. 6 is a rear elevational view;

FIG. 7 is a bottom plan view; and

FIG. 8 is a sectional view on line 8—8 of FIG. 1.

I claim:

The ornamental design for a waffle cooking plate, as shown.
